UNITED STATES PATENT OFFICE.

JOSEPH APPLEGATE HEMSLEY, OF TRENTON, NEW JERSEY.

VEHICLE-TOP.

No. 873,233.

Specification of Letters Patent.

Patented Dec. 10, 1907.

Application filed April 25, 1907. Serial No. 370,261.

To all whom it may concern:

Be it known that I, JOSEPH A. HEMSLEY, citizen of the United States, residing at Trenton, in the county of Mercer and State of 5 New Jersey, have invented new and useful Improvements in Vehicle-Tops, of which the following is a specification.

My invention relates to adjustable tops for wagons and other vehicles; and it contemplates the provision of a simple and easily 10 adjusted top embodying such a construction that the top when down does not take up any portion of the space in the vehicle body.

Other advantageous features of the invention 15 will be fully understood from the following description and claims when the same are read in connection with the accompanying drawings, forming part of this specification, in which:

20 Figure 1 is a side elevation illustrating a portion of a wagon embodying my invention; the top being shown as up. Fig. 2 is a broken rear elevation of my improvements. Fig. 3 is a detail horizontal section taken in 25 the plane indicated by line 3—3 of Fig. 2, looking downward. Fig. 4 is a detail view, on an enlarged scale, of the upper portion of one of the uprights of the novel top. Fig. 5 is a view similar to Fig. 1, showing the top as 30 down or in its idle position. Fig. 6 is a detail inverted plan view, and Fig. 7, a detail vertical section showing one of the curtain bars and the means for fastening the same.

Similar letters designate corresponding 35 parts in all of the views of the drawings, referring to which:

A is the body of the vehicle, which may be of any description without affecting my invention.

40 B is a seat of the ordinary or any other approved construction arranged on the body A in the usual or any other suitable manner, and C C are the uprights of my novel top. Each of the said uprights C is carried by a 45 lateral bracket D fixed to the seat B, and each is provided with a vertical, transversely-disposed guideway a, a housing b at its upper end, and a keeper c arranged in the upper portion of the guideway a and contained in 50 the housing b, as illustrated. For the sake of cheapness and durability, I prefer to construct the uprights C in the specific manner illustrated—that is to say, I prefer to have each upright comprise a main portion d of 55 gas pipe, a threaded stud e fixed in the lower end of the gas pipe portion and designed to

extend through an aperture in one bracket D to receive a nut f, a metallic strap g having a lateral apertured arm h at its lower end receiving the threaded stud e and interposed 60 between the lower end of the gas pipe portion d and the bracket D, and also having a lateral apertured arm i at its upper end positioned with its aperture in alignment with the gas pipe portion d, and sheet-metal or 65 other suitable material fixed to the gas pipe portion d and the strap g, and arranged to form the before described housing b. The keeper c in the housing b is preferably beveled and arranged relative to the other parts 70 of the upright after the manner best shown in Fig. 4. I also prefer to connect the uprights C in the manner shown—i. e., through the medium of a cross-rod E having depending portions j at its ends extending through 75 the upper apertured arms i of the straps g and down into the gas pipe portions d of the uprights. As will be readily appreciated uprights constructed and connected together in the specific manner just described constitute 80 an inexpensive supporting frame for a top and one that is well adapted to withstand the practical usage to which such devices are ordinarily subjected.

F is the top of my improvements, which 85 *per se* may be of any shape and construction compatible with the purpose of my invention, though I prefer to shape and construct the said top as illustrated. I also prefer to provide the side bars m of the top F with depending, headed projections n, and to detachably connect to the said headed projections bars G; the said bars being provided with apertures p to loosely receive the projections n, and being equipped with hooks q 95 which are pivoted to their under sides and are arranged to be swung into and out of engagement with the projections n to detachably fasten the bars on said projections. The bars G are designed to carry curtains H, 100 portions of which are illustrated, and by virtue of the construction described it will be apparent that the bars G may be expeditiously and easily connected to the side bars m of the top F when it is desired to use the curtains H 105 and may be as readily removed from the said side bars m when it is not desired to use the said curtains.

I I are lateral projections carried at the rear ends of the side bars m of top F and designed to rest and move at the rear sides of the straps g comprised in the uprights C. 110

J J are latches movable endwise in guides on the rear cross-bar of top F and through openings in the side bars m and normally extending beyond the side bars m so as to rest 5 and travel in the guideways a afforded between the gas pipe portions and the straps of the uprights C. K K are springs connecting the said latches and the top and designed to return the latches to and normally hold 10 the same in the positions stated.

L L are finger pieces movable in guides on the rear cross-bar of the top F and having rearwardly extending portions extending through and movable in a slot s in said rear 15 cross-bar, and M M are connections intermediate the said finger pieces and the latches J for moving the latter inward by the former. In this latter connection it will be noticed that when an operator draws the rearwardly 20 extended portions of the finger pieces L together, the latches J will be drawn inward against the actions of the springs K; also, that when the said finger pieces are released, the springs K will operate to throw the latches 25 outward and hold the same in an extended position relative to the top F.

P P are top-props, hinged at t to the seat B and at u to the forward portion of the top F. These props have for their office to serve 30 as stays in supporting the forward portion of the top F when the latter is in the position shown in Fig. 1, and by reference to Fig. 5 it will be seen that the said props do not interfere with the top F being placed in the idle position shown in said figure.

In the practical use of my improvements, the latches J serve when the top F is moved from the position shown in Fig. 5 to that shown in Fig. 1, to guide the rear portion of 40 the top in its vertical movement, and they also serve to ride up over and assume a position above the keepers c, and in that manner support the rear portion of the top F. When it is desired to lower the top or shift the 45 same from the position shown in Fig. 1 to that shown in Fig. 5, the operator has but to press the finger pieces L together so as to draw the latches J out of engagement with the keepers c, and then lower the rear portion 50 of the top F until the latches clear the keepers. The operator then releases the finger pieces L so as to enable the latches to resume their positions in the guideways a, and with this done moves the top F downward until its 55 rear cross-bar rests on top of the rear wall of the seat B. In this latter position the top F will be retained by gravity, and in such position it will be readily seen that the top takes up no part of the space in the body A of the 60 vehicle which is the chief advantage of my improvements. When it is desired to raise the top F from the position shown in Fig. 5 to that shown in Fig. 1, the operator has but to move the rear portion of the top F upward 65 until the latches J pass and assume a

position above the keepers c, when said latches will obviously secure the rear portion of the top in its raised position. Incident to the described adjustments of the top F, the props P will follow and accommodate themselves to the positions of the top F so as to brace and support the forward portion of the top when the latter is raised, and yet not interfere with the top being moved into the position shown in Fig. 5.

I prefer for obvious reasons to connect my novel top to the seat B of a vehicle, but I do not desire to be understood as confining myself to such arrangement for the reason that any part of a vehicle may be utilized as a support for my novel top without involving departure from the scope of my invention as defined in the appended claims.

Having described my invention, what I claim and desire to secure by Letters-Pat- 85 ent, is:

1. The combination of a support, uprights fixed to and rising from the support, keepers carried at the upper portions of the said uprights, a top arranged to be moved bodily from a raised horizontal position to a lowered upright position and vice-versa; said top having latches arranged to coöperate with the keepers of the uprights, and means for supporting the forward portion of the top 95 when the top is in its raised position.

2. The combination of a support, a top arranged to be moved bodily from a raised horizontal position to a lowered upright position and vice versa, uprights fixed to and rising from the support and connected with and arranged to guide the rear portion of the top in the vertical movements thereof and provided with means for supporting the said rear portion in its raised position, and props 100 extending between and pivotally connected to the support and the front portion of the top.

3. The combination of a support, uprights fixed to and rising from said support and having vertical guideways and keepers located in the upper portions of the guideways, an adjustable top, latches carried by the top and arranged in the guideways of the uprights and movable past the keepers and 110 adapted to assume positions above said keepers, and props connecting the said top with the said support.

4. The combination of a vehicle body, a seat carried thereby and having a rear wall, 120 uprights fixed to and rising from the end portions of the seat at the rear thereof and having vertical guideways and keepers located in the upper portions of the guideways, a top adjustable bodily and arranged when lowered to rest in a substantially upright position between the uprights and with its rear ends resting on the rear wall of the seat, latches carried by the top and arranged in the guideways of the uprights and movable 125 130

past the keepers and adapted to assume positions above said keepers, and props connecting the seat and the top.

5. The combination of a vehicle body, a seat carried thereby, uprights fixed to and rising from the end portions of the seat at the rear thereof and having vertical guideways and also having housings at their upper ends and beveled keepers arranged in the guideways and contained in said housings, a cross-bar connecting the upper portions of the uprights, an adjustable top, latches carried by the top and movable in the guideways of the uprights; said latches being movable in the direction of their length with respect to the top, springs for moving said latches outward, finger pieces connected with the latches and carried by the top and adapted for use in drawing the latches inward, and 20 props connecting the seat and the top.

6. The combination of a vehicle body, a seat carried thereby, uprights fixed to brackets on the seat and respectively comprising a gas pipe portion, a threaded stud fixed in the lower end of the gas pipe portion and extending through an aperture in one bracket, a nut arranged on the threaded stud below the bracket, a metallic strap arranged parallel to the gas pipe portion and having a lateral apertured arm at its lower end receiving the threaded stud and interposed between the bracket and the gas pipe portion, and also having a lateral apertured arm at its upper end, a housing arranged on the upper portions of the gas pipe portion and strap, and a beveled keeper arranged in the housing and between the gas pipe portion and the strap, a cross-bar having depending portions disposed in the upper apertured arms of the 40 straps and the upper ends of the gas pipe

portions of the uprights, an adjustable top, latches carried by the top and arranged in the guideways of the uprights and movable past the beveled keepers and adapted to assume positions above said keepers, and props 45 connecting the said top with the seat.

7. The combination of a support, uprights fixed to and rising from said support and having vertical guideways and keepers located in the upper portions of the guideways, 50 an adjustable top arranged to be adjusted from a horizontal position to a substantially upright position between the uprights and vice versa, means carried by the top and movable in the guideways of the uprights 55 and arranged to coöperate with the keepers in the guideways in supporting the top in its horizontal position and props extending between and pivotally connected to the support and the front portion of the top. 60

8. The combination of a vehicle body, a seat carried thereby, fixed uprights rising from the end portions of the seat at the rear thereof and provided adjacent to their upper ends with top-supporting means, a top connected at its rear with the uprights and arranged to be moved from a raised horizontal position in front of the uprights to a lowered substantially upright position and vice versa, and also arranged to be engaged by the said 65 top-supporting means of the uprights, and means for supporting the front portion of the top. 70

In testimony whereof I have hereunto set my hand in presence of two subscribing 75 witnesses.
